UNITED STATES PATENT OFFICE.

BENJAMIN FRANKLIN BRUMAGHIM, OF MOUNT HOPE, WEST VIRGINIA.

CAR.

No. 895,240.

Specification of Letters Patent.

Patented Aug. 4, 1908.

Application filed November 14, 1907. Serial No. 402,120.

To all whom it may concern:

Be it known that I, BENJAMIN FRANKLIN BRUMAGHIM, a citizen of the United States, and a resident of Mount Hope, in the county of Fayette and State of West Virginia, have made certain new and useful Improvements in Cars, of which the following is a specification.

My invention is an improvement in cars and consists in certain novel constructions and combinations of parts hereinafter described and claimed.

Referring to the drawings forming a part hereof—Figure 1 is a side view of the car in its normal position. Fig. 2 is a similar view in dumping position. Fig. 3 is an end view in normal position, and Fig. 4 is a transverse vertical section showing the car in dumping position.

The present embodiment of my invention, comprises a car having a frame 1, supported by wheels 2 in the ordinary manner, the wheels being adapted to run upon a track 30, which is provided with a depressed portion 31 for a purpose to be hereinafter described.

The bottom of the car is composed of two leaves 3, 3^a, arranged longitudinally of the car and abutting at their inner ends, the outer edges of the leaves being hinged to the frame 30 as at 4. The car is provided at each side near the bottom with a swinging door 5, extending the full length of the car and hinged at its upper edge as at 6, the lower edge of the door being adapted to contact with the outer edge of the bottom as shown in Fig. 3, whereby to completely close the car. The ends 9^a of the car are solid as shown in Figs. 3 and 4, and that portion of the frame above the side doors is also inclosed as indicated at 10^a.

Each of the side doors 5, is provided at each end with a block 7, having a notch 8, adapted to be engaged by a locking bar 9, the locking bar extending the full length of the car and having angular ends 11, which ends are pivoted on a pin 10 connected with a plate 12 secured to each end of the car as shown in Fig. 3.

A pair of aligned levers 15, are pivoted to each side of the car by their adjacent ends as at 16, and the free ends of the levers are connected by links 13, with the locking bars 9 before described.

A U-shaped hanger 21 is arranged to slide vertically in bearings 22 on each side of the car, and a shaft 20 is arranged transversely

of the U-shaped hanger. A wheel 19 is journaled on the shaft between the arms of the hanger, and a bar 18 is secured to the inner end of the shaft between the hanger 60 and the side of the car. Links 17 connect the ends of the bar with the levers as shown in Figs. 1 and 2, the said links being connected with the levers near the free ends thereof.

A supplemental rail 32 is arranged upon each side of the track 30, and the said rails are normally engaged by the wheels 19 on each side of the car. It will be evident from the description, that when the wheels of the 70 car run into the depression 31 of the track, the wheels 19 will be elevated, thus elevating the U-shaped hangers and the outer ends of the levers 15, which through the link connection 13 will lift the locking bars 9 out of the 75 notches 8, thus permitting the weight of the material in the car to force the side doors 5 outwardly as shown in Fig. 5.

The angular ends 11 of the locking bars 9, are provided with pins 23, engaging in slots 80 25 in the ends of a cross bar 24, which is provided at its center with a bearing 26, through which passes a bolt 27, connecting the bar with the end of a beam 29 which extends the full length of the car immediately below the 85 junction of the leaves of the bottom, the said beam being provided at intervals with shoes 33, which are adapted to engage and lift the leaves of the bottom as shown in Fig. 4, when the locking bars are lifted.

It will be evident from the description that the lifting of the leaves of the bottom will not begin until the side doors have been opened to some extent and a portion of the contents of the car permitted to escape, on account of 95 the lost-motion connection between the bar 24 and the angular ends 11 of the locking bars.

While I have described the track 30 as being provided with a depression 31 into which 100 the car moves, it is obvious that the supplementary rails 32 might be provided with elevated portions for lifting the wheels 19 whereby to operate the dumping mechanism.

It will be observed, that the car dumps its 105 load while moving and that as soon as the car moves out of the depression 31, the parts will be restored to their normal position and the locking bars 9 will again lock the parts in the position shown in Fig. 3.

I claim—

1. A car comprising a wheel supported

frame, a bottom composed of a plurality of edgewise abutting leaves arranged longitudinally of the car and hinged at their outer edges, side doors extending the full length of the frame and hinged by their upper edges to swing outwardly from the frame, a locking means for the side doors, said means comprising bars extending the full length of the car and having angular ends pivotally connected with the ends of the car, a pair of aligned levers on each side of the car, the adjacent ends of the levers being pivoted to the car, links connecting the free ends of the levers with the locking bar on the corresponding side of the car, a U-shaped bracket 75 slideable vertically on each side of the car, a wheel journaled in the bracket, a bar connected with the wheel and extending longitudinally of the car, links connecting the ends of the bar with the levers, a beam extending longitudinally of the car beneath the abutting edges of the leaves of the bottom and provided with shoes for engaging the leaves, a bar arranged transversely at each 80 end of the car and having a lost-motion connection with each of the locking bars, a connection between each of said bars and the beam, and supplementary rails for engagement by the wheels to elevate the brackets.

2. A car comprising a wheel supported frame, a bottom composed of a plurality of edgewise abutting leaves arranged longitudinally of the car and hinged at their outer edges, side doors extending the full length of the frame and hinged by their upper edges to swing outwardly from the frame, a locking means for the side doors, said means comprising bars extending the full length of the car and having angular ends pivotally connected with the ends of the car, vertically 85 movable brackets on the sides of the car, wheels journaled in the brackets, a connection between the respective brackets and locking bars, a beam extending longitudinally of the car beneath the abutting edges of the leaves of the bottom and provided with 90 shoes for engaging the leaves, a lost-motion connection between the locking bars and the beam, and supplementary rails for engaging the wheels to elevate the brackets.

3. A car comprising a wheel supported frame, a bottom composed of a plurality of edgewise abutting leaves arranged longitudinally of the car and hinged at their outer edges, side doors extending the full length of the frame and hinged by their upper edges to swing outwardly from the frame, a locking 95 means for the side doors, said means comprising bars extending the full length of the car and having angular ends pivotally connected with the ends of the car, a pair of aligned levers on each side of the car, the adjacent ends of the levers being pivoted to the car, links connecting the free ends of the levers with the locking bar on the corresponding side of the car, a U-shaped bracket slideable vertically on each side of the car, a wheel journaled in the bracket, a bar connected with the wheel and extending longitudinally of the car, links connecting the ends of the bar with the levers, a beam extending longitudinally of the car beneath the abutting edges of the leaves of the bottom and provided with shoes for engaging the leaves, a lost-motion connection between the locking bars and the beam, and supplementary rails for engaging the wheels to elevate the brackets.

4. A car comprising a wheel supported frame, a bottom composed of a plurality of edgewise abutting leaves arranged longitudinally of the car and hinged at their outer edges, side doors extending the full length of the frame and hinged by their upper edges to swing outwardly from the frame, a locking means for the side doors, said means comprising bars extending the full length of the car and having angular ends pivotally connected with the ends of the car, vertically 100 movable brackets on the sides of the car, wheels journaled in the brackets, a connection between the respective brackets and locking bars, a beam extending longitudinally of the car beneath the abutting edges of the leaves of the bottom and provided with shoes for engaging the leaves, a lost-motion connection between the locking bars and the beam, and supplementary rails for engaging the wheels to elevate the brackets.

5. A car comprising a wheel supported frame, a bottom composed of a plurality of edgewise abutting leaves arranged longitudinally of the car and hinged at their outer edges, side doors hinged by their upper edges to swing outwardly from the frame, a locking means for the side doors, said means comprising bars extending the full length of the car and having angular ends pivotally connected with the ends of the car, vertically 105 movable brackets on the sides of the car, wheels journaled in the brackets, a connection between the respective brackets and locking bars, means for lifting the abutting edges of the leaves of the bottom, a lost-motion connection between the locking bars and the lifting means, and supplementary rails for engaging the wheels to elevate the brackets.

6. A car comprising a wheel supported frame, a bottom composed of a plurality of edgewise abutting leaves arranged longitudinally of the car and hinged at their outer edges, side doors hinged by their upper edges to swing outwardly from the frame, a locking means for the side doors, vertically 110 movable brackets on the sides of the car, a connection between the respective brackets and locking bars, means for lifting the abutting edges of the leaves of the bottom, a lost-motion connection between the locking bars and the lifting means, and supplementary rails for engaging the wheels to elevate the brackets.

7. A car comprising a wheel supported frame, a bottom composed of a plurality of edgewise abutting leaves arranged longitudinally of the car and hinged at their outer edges, side doors extending the full length of the frame and hinged by their upper edges to swing outwardly from the frame, a locking 115 means for the side doors, said means comprising bars extending the full length of the car and having angular ends pivotally connected with the ends of the car, a pair of aligned levers on each side of the car, the adjacent ends of the levers being pivoted to the car, links connecting the free ends of the levers with the locking bar on the corresponding side of the car, a U-shaped bracket slideable vertically on each side of the car, a wheel journaled in the bracket, a bar connected with the wheel and extending longitudinally of the car, links connecting the ends of the bar with the levers, a beam extending longitudinally of the car beneath the abutting edges of the leaves of the bottom and provided with shoes for engaging the leaves, a lost-motion connection between the locking bars and the beam, and supplementary rails for engaging the wheels to elevate the brackets.

8. A car comprising a wheel supported frame, a bottom composed of a plurality of edgewise abutting leaves arranged longitudinally of the car and hinged at their outer edges, side doors hinged by their upper edges to swing outwardly from the frame, a locking means for the side doors, vertically 120 movable brackets on the sides of the car, a connection between the respective brackets and locking bars, means for lifting the abutting edges of the leaves of the bottom, a lost-motion connection between the locking bars and the lifting means, and supplementary rails for engaging the wheels to elevate the brackets.

between the brackets and the locking means, means for lifting the abutting edges of the leaves of the bottom, a lost-motion connection between the locking means and the lifting means, and means for elevating the brackets.

7. A car comprising a wheel supported frame, side doors extending the full length of the sides of the frame and hinged by their upper edges to swing outwardly therefrom, a locking means for the doors, said means comprising bars extending the full length of the car and having angular ends pivotally connected with the ends of the car, vertically movable brackets on the sides of the car, wheels journaled in the brackets, a connection between the respective brackets and locking bars, and supplementary rails for engaging the wheels to elevate the brackets.
8. A car comprising a wheel supported frame, a bottom composed of a plurality of edgewise abutting leaves arranged longitudinally of the car and hinged at their outer edges, doors hinged by their upper edges to the sides of the frame and swinging outwardly therefrom, a locking means for the side doors, a beam extending longitudinally

of the car beneath the abutting edges of the leaves of the bottom and provided with shoes for engaging the leaves, a lost-motion connection between the locking means and the beam, and means for operating the locking means to release the side doors.

9. A car provided with side doors and with a bottom composed of edgewise abutting leaves arranged longitudinally of the car, a locking device for the side doors, means for elevating the abutting edges of the leaves of the bottom, and a lost motion connection between the leaf lifting means and the locking device.

10. A car provided with side doors and with a bottom composed of edgewise abutting leaves arranged longitudinally of the car, a locking device for the side doors, means for elevating the abutting edges of the leaves of the bottom, and means for releasing the locking device and operating the lifting means in sequence.

BENJAMIN FRANKLIN BRUMAGHIM.
